PILFERPROOF BOX

James P. H. Leavitt, New Haven, Conn.

Application November 4, 1931. Serial No. 572,899

4 Claims. (Cl. 229—47)

This invention relates to a pilfer-proof box and more particularly to a fiber board or corrugated board box which is so formed and sealed that access to the same cannot be had without destroying a strong stapled connection between the box body and the cover body therefor.

The principal object of this invention is to provide such a box composed of a body and a cover in which the cover body can be quickly, 10 easily and inexpensively sealed by stapling, stitching or the like to the box body so that the box is rendered difficult to open and any attempt to pilfer the box is immediately detectable.

Another object is to provide a light, strong, inexpensive, durable and rigid box which can be easily set up, sealed and can be stapled or sewed without using sealing tape or rope, string or wire, and when closed by sewing or stapling provides a box which adequately protects the contents 20 from the entrance of dirt or moisture.

Another object of this invention is to provide a pilfer-proof box construction which can be embodied in boxes of any desired form or size.

A still further object is to provide such a box in 25 which a large saving in fiber board can be effected, particularly as compared with boxes of standard types now being used. The invention also permits this saving to be effected either in the cover body or in the box body thereby permitting of effecting the greatest economy for the particular size and form of box being made.

Another purpose is to provide a means of sealing a box against pilfering which is particularly adapted for suit boxes which have comparatively 35 broad and long covers and to be effectively sealed against pilfering require that they be sealed substantially their entire length and breadth.

In the accompanying drawings:

Figure 1 is a perspective view of a closed, single 40 ply fiber board box made and sealed against pilfering in accordance with my form of invention in which the saving in fiber board is effected in the cover body.

Figure 2 is a perspective view of a double ply 45 fiber board box body made in accordance with the invention showing the same ready to have the cover body applied and sealed thereto.

Figure 3 is a cross section through the cover 50 body and box body of the form of box shown in Figure 1, showing the cover body sealed to the box body and the box thereby sealed against pilfering.

Figure 4 is a view similar to Figure 3 showing the invention applied to a one piece box.

55 Figure 5 is a perspective view of a cut blank

of a box body employed in making the modified form of the invention shown in Figs. 5-7 in which the saving in material is effected in the box body.

Figure 6 is a view of the blank shown in Fig. 5 60 folded up and stapled.

Figure 7 is a view showing a cover body applied and stapled to the box body shown in Fig. 6.

Similar reference numerals refer to similar parts in each of the views.

In its general organization this invention comprises a box body having outwardly reversely deflected portions along the edges of its walls, and a cover body the walls of which extend over these outwardly and reversely deflected portions so 70 that by passing the blade anvil of a stapling machine under these deflected portions and under the cover body walls, the cover body walls can be stapled to these deflected portions and thereby seal the cover body to the box body and prevent 75 pilfering of the contents of the box. The invention also comprehends a saving of material as will be hereinafter described.

In the form of the invention shown in Figs. 1-3, this saving of material is effected in the 80 cover body. As there shown the box comprises a box body indicated generally at 10 and a separate cover body indicated generally at 11. The box body comprises a bottom 12, front and rear walls 13 and 14 rising from the front and rear 85 edges of the bottom 12 and side walls 15 and 16 rising from the side edges of the bottom 12. These walls can be secured at their corners in any suitable manner as by providing flaps 17 at the ends of the side walls 15 and 16, which flaps 90 17 overlay the ends of the front and rear walls 13 and 14 and are secured thereto by a row of staples 18 or in any other suitable manner. Each of the box body walls is formed to provide an outwardly and reversely or downwardly deflected 95 portion 19 arranged along the outside of each body wall. This deflected portion is shown as formed by slitting each box body wall downwardly near the ends thereof as indicated at 20, bending the board between these slits outwardly 100 and downwardly to form the deflected portion 19 and then passing a row of staples 21 through the upper part of this deflected portion 19 and the adjacent part of the corresponding box body wall.

The cover body 11 is composed of a top 22 having front and rear cover body walls 23 and 24, and side cover body walls 25. The cover body walls can be secured at their corners in the same manner as the box body walls by providing flaps 26 110

at the ends of the front and rear cover body walls 23 and 24, which flaps 26 overlay the side cover body walls 25 and are secured thereto by staples 27 or the like.

- 5 In sealing the box the cover body 11 is placed over the box body 10 and the cover body walls 23, 24 and 25 overlay the deflected portions 19 of the box body walls. A row of staples 28 is passed through the outwardly and reversely deflected portions 19 and the adjacent part of the corresponding cover body wall. The invention is not limited to stapling, however, and the box body and cover body could be sealed by sewing or in any other suitable manner. Each of the deflected portions 19 is stapled or sewed to the corresponding cover body wall and it is therefore apparent that when completed the cover body is stapled or sewed at all of its sides to the box body for substantially the entire length and width of the 10 box and that therefore the box is closed and sealed throughout and pilfering of the same is impossible without substantial destruction of the deflected portions 19 or of the box.

It is also apparent that this invention can be 20 applied to a box in which the cover body is integrally secured at one side to the box body. Such a construction or one-piece box construction, is illustrated in Figure 4 which also shows the manner in which the invention can be embodied in a box made of corrugated fiber board.

In this construction the box body 10a has a bottom 12a, front and rear walls 13a and 14a rising from the bottom 12a and side walls 15a and 16a which rise from the side edges of the 30 bottom 12a. The extended corners 30 of these walls are creased and folded inwardly and against the inner faces of the front and rear walls 13a and 14a and sealed thereto by staples 31. The rear body wall 14a is extended to form the top 40 22a of the cover body 11a and this cover body is provided with a depending front wall 23a and side walls 25a. These cover body walls are secured at their corners by providing flaps 26a at the ends of the front cover body wall 23a and sealing these flaps against the sides of the side 45 cover body walls 25a by staples 27a.

The side and front box body walls 15a, 16a and 50 13a are each formed to provide outwardly and reversely or downwardly deflected portions 19 which are formed identical to the deflected portions 19 in the form shown in Figures 1-3 and are stapled or sewed at their upper edges to the corresponding box body wall by a row of fastenings or staples 21 as in the first construction. It 55 is apparent that when the cover body 11a is folded over the box body 10a the cover body walls 23a and 25a overlay the deflected portions 19 and can be stapled thereto by means of the row of staples 28 in the same manner as with the construction 60 shown in Figures 1-3.

In the forms of the invention shown in Figs. 1-4, it is apparent that a saving of material is effected in the cover body of the box. Thus it will be noted that the walls 23, 24 and 25 of the 65 cover body are narrow, the same being made only wide enough to extend downwardly far enough to extend over and cover the outwardly and reversely deflected portions 19. Since the standard practice is to extend the walls of the cover body to extend the full height of the box body walls, it is obvious that a much smaller blank can be used in forming the cover body of the present box and hence that a great saving of material is effected at the same time that a sealed, pilfer-proof box is provided.

In Figs. 5-7 a box is shown in which this saving is effected in the box body instead of the cover body as in Figs. 1-4. This form corresponds in general to the form shown in Figs. 1-3, the box body 10b having a bottom 12b, front and rear walls 13b and 14b rising from the front and rear edges of the bottom 12b and side walls 15b and 16b rising from the side edges of the bottom 12b. Similarly these walls are secured at their corners by flaps 17b at the ends of the side walls 15b, and 16b, which flaps overlay the ends of the front and rear walls 13b and 14b and are secured by a row of staples 18b or in any other suitable manner. In the same manner each of the box body walls is formed to provide an outwardly and reversely or downwardly deflected portion 19b formed by slitting each box body wall as at 20b, and bending the board between these slits outwardly and downwardly.

It will be noted that in this construction the side box body walls 15b and 16b are of full height but that the end box body walls 13b and 14b are narrow, these end body walls being only high enough to permit of forming the outwardly and reversely deflected portion 19b therein. By so doing it is apparent that the blank for the box body is shorter since if all the box body walls were made of full height, the box body blank would be lengthened to the extent indicated by the dotted lines 35 shown at opposite ends of Fig. 105 5. It is obvious, therefore, that a substantial saving of material in the box body is effected in the form of the invention shown in Figs. 5-7.

In this form the walls 23b, 24b and 25b of the cover body 11b extend the full height of the box 110 body 10b and is in other respects identical to the cover body shown in Figs. 1-3, the side cover body walls being provided at their ends with flaps 26b fastened to the end cover body walls by staples 27b or in any other suitable manner. In this 115 form, the box is sealed by placing the cover body over the box body and passing a row of staples or stitches 28b through each cover body wall and the deflected portions 19b formed on the box body walls.

In all of the forms of the invention, the box body and cover body is sealed along all four sides and substantially the entire length of the side walls so that the box cannot be opened without substantial destruction of the box and an unlawful opening of the box is immediately detectable 125 thereby enabling the consignee to refuse to accept the box until an inspection has been made; the box is also sealed against the entrance of dust and dirt; is light, strong and durable; can be 130 easily sealed; the invention can be embodied in any standard form of box and a saving of material can be effected either in the cover body or the box body without in any way sacrificing the strength or rigidity of the box.

I claim as my invention:

1. A box of the character described, comprising a box body having a bottom and side walls rising from said bottom, a cover body having a top and at least one side wall depending from said top and adapted to fit over at least one of said box body side walls, and an outwardly and downwardly deflected portion formed in said box body side wall by slitting said box body side wall downwardly from its upper edge at two places and bending the intermediate part downwardly and outwardly to form said deflected portion, said deflected portion being arranged between said box body and cover body side walls and said deflected portion being adapted to be secured at its lower 150

- end to said cover body side wall by fastenings extending therethrough. 80
2. A box of the character described, comprising a box body having a bottom and side walls rising from said bottom, a cover body having a top and at least one side wall depending from said top and adapted to fit over at least one of said box body side walls, an outwardly and reversely deflected portion formed in said box body side wall by slitting said box body side wall a relatively short distance downwardly from its upper edge and bending the intermediate part downwardly and outwardly to form said deflected portion, said deflected portion being arranged between each box body side wall and the corresponding cover body side wall and each of said deflected portions being adapted to be secured to the corresponding cover body side wall by a row of fastenings extending therethrough, each of said cover body side walls terminating substantially at the lower edge of the corresponding deflected portion. 85
- 10 15 20
3. A box of the character described, comprising a box body having a rectangular bottom and four side walls rising from said bottom, a cover body having a rectangular top and at least three side walls depending from said top and adapted to fit over the corresponding box body side walls, an outwardly and reversely deflected portion formed in each of said box body side walls by slitting each of said corresponding box body side walls downwardly from its upper edge and adjacent each end thereof and bending the intermediate part downwardly and outwardly to form said deflected portion, said deflected portion being arranged between each box body side wall and the corresponding cover body side wall and each of said deflected portions being adapted to be secured to the corresponding cover body side wall by a row of fastenings extending therethrough, each of said cover body side walls terminating substantially at the lower edge of the corresponding deflected portion. 90
- 25 30 35
4. A box of the character described, comprising a box having a bottom and four walls rising from said bottom, two opposite walls of said box body being of less height than the other two, a cover body having a top and four walls adapted to fit over and substantially enclose the walls of said box body and an outwardly and reversely formed portion formed in each of said box body side walls by slitting each box body side wall at two places and bending the intermediate portion outwardly and downwardly so that its outer edge is arranged adjacent the low end of its box body side walls, each of said deflected portions being adapted to be secured at its lower end to the adjacent cover body side wall by fastenings extending therethrough. 100
- 40 45 50 55 60 65 70 75 80 85 90 95 100 105 110 115 120 125 130 135 140 145 150
